GEORGE W. HOLLINGSWORTH, OF CINCINNATI, OHIO.

PRINTING-MACHINE.

1,121,250.

Specification of Letters Patent. Patented Dec. 15, 1914.

Application filed November 12, 1910. Serial No. 591,944.

To all whom it may concern:

Be it known that I, GEORGE W. HOLLINGSWORTH, a citizen of the United States, residing at Cincinnati, in the county of Hamilton and State of Ohio, have invented a new and useful Printing-Machine, of which the following is a specification.

My invention relates to a hand operated printing machine, and more particularly to a machine in which rubber type are used.

The object of my invention is to provide a device which is comparatively inexpensive to manufacture, simple in construction and arrangement and easy to operate, so that the printing may be done by any one who can read.

Another object of my invention is to provide simple and efficient means for accomplishing the alinement of the face of the type.

Another object of my invention is to provide ready means for substituting one type form for another.

Another object of the invention is to provide means for equalizing the pressure upon the face of the type to insure evenness in printing.

Another object of my invention is to provide means whereby the copy to be printed is displayed upon the back of the type at all times, and in full view of the operator, thus enabling quick changes and substitutions of the matter to be printed and without danger of making mistakes.

My invention is particularly adapted to printing menu cards, or other printed matter requiring few changes, and with these and other objects in view, my invention consists in a type printing machine comprising a base, a printing platen, an open form suspended above said platen, type arranged in said form, an inking pad placed at one side of said platen and a slide rod adapted to carry the form and type back and forth from the inking pad to the platen.

My invention also consists in the details of construction and arrangement and in the parts and combination of parts as herein set forth and claimed.

In the accompanying drawing which serves to illustrate the construction and use of my invention: Figure 1 is a top or plan view of the device showing, at the right, the printing form in position for printing, and, at the left, an inking pad. Fig. 2 is a vertical section on the line A—B of Fig. 1. Fig.

3 is an end elevation. Fig. 4 is an enlarged detail end elevation of the frames and means for detachably connecting and holding them together. Fig. 5 is a side elevation of a spacing blank shown full size. Fig. 6 is a top view of the same. Fig. 7 is a top view of a metal bridge, and Fig. 8 is a side elevation of same mounted in position upon the side rods of the printing form, which rods are shown in section. Fig. 9 is a perspective view of a rectangular block of wood having upon its lower edge rubber type, and upon its upper edge a print thereof. Fig. 10 is a perspective view of a filling block.

In the embodiment of my invention, as illustrated and which shows a preferred construction, I provide a base 1, upon which I mount a rod 2, held in place by supports 3, 3' and 3''. Slidably mounted upon the rod 2 is an outer carrying frame 4, it being attached to the rod by bearings 5 and 5'. The frame is provided with a suitable handle 6. Placed within frame 4 is a type holding form 7, consisting of cross-bars 8 and 8' at each end, connected together at the sides by rods 9. Pivots 10 and 10' are secured to the cross-bars 8 and 8' respectively, and are detachably held in open bearings 11 on the lower sides of the carrying frame 4 by means of springs 12 and 12'. These springs are preferably constructed as clearly shown in Figs. 1, 3 and 4, in which they are shown as U-shaped and pivoted at one end 13 to the carrying-frame 4, and the other end of said springs are curved and clamp beneath said pivots 10 and 10' to hold said type form 7 in fixed longitudinal relation to the carrying frame 4, but allowing it to turn on said pivots 10 and 10'.

While it is not absolutely necessary for the form 7 to turn freely upon the pivots 10 and 10' to make a printed impression yet if it does not turn upon said pivots it will be seen that the outer edge of the printing form 7, being farther from the fulcrums or rod 2 than the other portions of the printing form will move faster than the inner edge thereof and in consequence the type will print heavier on one portion of the form than on the other; also if a number of sheets of paper are placed on the platen at one time the swinging form 7 will adjust itself automatically.

The type holding form 7 is provided with a series of spacing blanks 14, having extend-

ing lugs 15 at their ends to support them in position upon the side rods 9. These spacing blanks are provided to separate the lines of type and also serve to hold them in place. 5 They are also provided with bridges 16 (as shown in Figs. 7 and 8) having recessed ends adapted to engage the rods 9 and to be held in fixed vertical relation to said rods, and slideable longitudinally thereon. These 10 bridges are preferably formed of metal and are provided to hold the type rigidly in place when all are clamped together, and also to prevent the type from springing upward while under pressure when inking or printing. 15 Transverse extensions 17 are preferably provided on one end of the bridges 16 to engage the upper and lower surfaces of the rod 9 to hold the bridge and type in vertical position while the type form is 20 being set up.

As shown in Fig. 9, a section of rubber type 18 is preferably mounted upon the lower edge of a rectangular block of wood 19, which has upon its upper edge a print or 25 label 20 of said type. A thumb screw 21 is mounted in and extends through the type holding frame bar 8' and pivot 10' for the purpose of clamping the type, spacing blanks and bridges together. A platen or 30 type alining surface 22 is mounted upon the base 1 beneath the type holding form 7, and is provided upon its outer, upper surface with supports 23 adapted to engage type holding form 7 and hold it in proper relation to the platen, so that the face of the type 35 when being set will drop down into contact with the platen below the lower edges of the form, and after being clamped the form will remain above the face of the type 40 and will not come in contact with the inking pad or paper. When it is desired to set the type, place or arrange them in such positions as desired with spacing blanks and bridges interposed between the rows of 45 type at suitable distances apart in order to space the rows of type sufficiently apart and hold them in position. Ordinarily a bridge is required every four or five lines and a spacing blank is generally used between 50 each row of type. The space between the lines is regulated by the thickness of the spacing blank and one or more spacing blanks as desired, may be used between the lines. Where the lines of type are not complete, the intervening spaces are provided 55 with filling blocks 24 as shown in Fig. 10, and these filling blocks are provided with knobs 25 by which they are handled, and are provided with shoulders 25' extending laterally for the purpose of engaging the 60 spacing blanks or type blocks and holding the filling blocks above the platen.

In the use of my invention I preferably provide a resilient pad 26 formed of felt or other suitable material, which is placed upon

the platen or type alining surface 22 after the type have been set and clamped in place. This insures a complete engagement of the entire face of each type with the paper, and results in a clear, distinct impression of all 70 of the type. By inserting the resilient pad, the pressure exerted in printing is brought to bear upon the paper and resilient pad instead of upon pins 23 which support the type holding form 7. The longitudinal 75 rigidity of parts being essential, it is necessary to have the fulcrums of the carrying frame in fixed relation with the base. I therefore provide the central support 3' for the rod 2, so that when the 80 printing form is in position for printing or for inking, one of the bearings of the carrying frame 4 will be in contact with one of the outer supports, and the other bearing will be in contact with the central support, 85 thus insuring the rod 2 against being sprung upward when there is downward pressure upon the handle 6 in printing or inking. A supply and type drawer 27 is 90 preferably provided in the base of the machine.

The operation of my device is as follows: Slide the carrying frame 4 as far to the right as possible, as shown in Fig. 1, the type holding form 7 being mounted within 95 the carrying frame 4 and resting upon the supports 23 as shown in Fig. 2. Place the lines of type face downward upon the platen or type alining surface, displaying same in such position as will produce the most desired effects, using spacing blanks 14 and bridges 16 between said lines of type to properly space and hold the type. The filling blocks 24 are inserted in the spaces not occupied by the type. The spacing 100 blocks, bridges, type and filling blocks are then clamped together securely by means of a thumb-screw 21. The frame is then raised for the purpose of placing a resilient pad 26 upon the platen to insure a perfect 105 contact between the paper placed thereon to be printed and the face of the type. The printing is then accomplished by simply sliding the form to the left over the inking pad 28 and pressing downwardly to ink the 110 type by engagement therewith, then sliding the printing form to the right in position over the platen and pressing the form downwardly upon a sheet of paper to be printed, and repeating the operation. When it is 115 desired to substitute one printing form for another within the machine, the type holding form 7 is removed from the carrying frame 4 by simply raising the springs 12 upwardly upon their pivots 13 until their 120 free curved ends are disengaged from the pivots 10 and 10'. This will permit the carrying frame to be raised by the handle 125 out of engagement with the type form, which will then rest upon the pins 23, and 130

another type form can then be substituted, by merely reversing the operation just described.

It will be seen that this machine is one of great simplicity and economy of construction, and is adapted to be used by any person who can read without any special knowledge in type setting or printing. This makes it especially useful and desirable in hotels and restaurants where daily changes in the items to be printed are necessary. It requires but a few minutes to make such changes without setting separate letters or even words, the lines of rubber type being made to suit the requirements of the individual user. An especially desirable feature is that each line or portion of a line of type is labeled on the upper edge so that the entire card or other matter to be printed is in plain print precisely where it is to be printed, and this enables the user to rearrange the items and substitute others without reference to the face of the type or printing a copy or without removing it from the device. The user is less liable to make mistakes in this way than otherwise. In addition to being simple and easy of operation, the type automatically line up to a true printing surface, thus giving an even, clear impression unobtainable in other rubber type machines, owing to the fact that it is impossible to make rubber type of equal thickness.

Many modifications of my invention may be made without departing from its spirit and scope, as for instance, if desired metal type may be employed instead of rubber type, and for this reason I do not wish to be confined to the particular construction and arrangement of parts set forth or to the materials used in their construction.

I claim:

1. In a type printing machine, a base, an inking pad on said base, a fixed rod mounted on said base, a platen, a slideable carrying frame fulcrumed on said rod, a type holding form having pivots mounted in said slideable carrying frame and means for moving said type holding form and slideable carrying frame and bringing the type into engagement with the inking pad and the platen, alternately, substantially as set forth and for the purposes specified.

2. In a type printing machine, a base, an inking pad and platen on said base, a fixed rod mounted above said base, a slideable carrying frame pivotally mounted on said rod, a type holding form carried by said frame and a handle attached to said frame for moving said frame to alternately engage the type with the inking pad and the platen, substantially as set forth and for the purposes specified.

3. In a printing machine, a base, three supports thereon, a rod forming a fulcrum

held by said supports, an inking pad and platen upon said base, a slideable carrying frame having two bearings slidably mounted on said rod, each of said bearings adapted to engage the outer supports, and both of said bearings adapted to alternately engage the inner support whereby said fulcrum is maintained in absolutely fixed relation to the base at all times, when the printing form is in engagement with the inking pad and the platen respectively.

4. In a printing machine, a base, an inking pad and platen mounted thereon, a slide rod mounted on three supports, a slideable carrying frame having two bearings, one on either side of the center support, a printing form carried in said carrying frame, and a handle to operate same.

5. In a printing machine, a base, a pivotally mounted type holding form, having pivots centrally located on each end approximately in its plane, a frame having recesses adapted to receive said pivots, type arranged in said form, a platen, an inking pad at one side of said platen and a fixed slide rod adapted to carry the type holding form back and forth from the inking pad to the platen, substantially as set forth.

6. In a printing machine, a base, an inking pad, a platen, a fixed rod, a slideable carrying frame mounted on said rod, a type holding form pivotally mounted in said slideable carrying frame, springs and bearings adapted to detachably hold said form within said slideable carrying frame, substantially as set forth.

7. In a printing machine, a base, an inking pad and a platen thereon, a fixed slide rod mounted on said base, a type holding form slidably and pivotally mounted on said slide rod, and means for supporting said form out of contact with the said platen.

8. In a printing machine, a base, an inking pad, a platen on said base, an open type form pivotally mounted above said platen, type inserted from the top and arranged in said open form, face downwardly on said platen, bridges between the lines of type carried by the sides of said open form in a fixed vertical relation thereto, but slideable thereon, means for clamping the bridges and type together, and means for operating said form, substantially as set forth.

9. In a printing machine, a platen, a carrying frame, an open type form pivotally mounted in said frame at each end approximately in its own plane above said platen, type inserted from the top and aligned by their faces dropping to a true surface upon the platen, and means for holding the type securely clamped in said form, substantially as set forth.

10. In a printing machine, a platen, a slideably mounted carrying frame, an open type form pivotally mounted at each end in the

plane of said form, bridges and spacing blanks extending from side to side of said frame and lines of type inserted from the top, the type faces alined upon said platen, 5 the type being clamped between said spacing blanks and bridges, substantially as set forth.

11. In a printing machine, a base, an inking pad and platen, a carrying frame slidably mounted above said base, and having 10 open bearings upon its lower side, a type holding form within said carrying frame, a pivot secured at each end of said type holding form and adapted to turn in said bearings, a U-shaped spring pivotally mounted at one of its ends on said carrying frame and having a free end curved to engage and hold each pivot within said open bearings and adapted to be released therefrom to disengage 15 said frames by turning said spring upwardly upon said pivots, substantially as set forth.

12. In a printing device, a base, fixed pivots suitably mounted thereon, a platen, an 20 open form and type clamped therein, pivots centrally located on the ends and approximately in the plane of said form, a carrier mounted on said fixed pivots having pivot bearings equidistant from said fixed pivots to carry the pivots of the form allowing the 25 form to turn on the pivots freely in said recesses.

13. In a printing device, a platen, an open 30 form having parallel side rods, type inserted from the top and arranged in said open form face downwardly on said platen, bridges between the lines of said type having ends which slidably straddle said parallel side rods and hold said bridges in fixed vertical 35

relation to said side rods, and means for 40 clamping the type and bridges together.

14. In a printing device, a base, pivots suitably mounted thereon, two frames one within the other, the outer frame mounted at one edge on said pivots, and the inner 45 frame having pivots centrally located in the end approximately in its plane, the outer frame having two recesses parallel to the fixed pivots to receive the pivots of the inner frame, type clamped in said inner frame, 50 and means for alternately raising said frames and bringing pressure to bear on said type.

15. In a printing device, a base, a slide rod rigidly mounted on said base, a carrying 55 frame slidably mounted on said rod, a type form mounted pivotally parallel to said rod in said carrying frame, type clamped in said form, and a clamp screw extending longitudinally through the pivot with means for 60 operating outside of the carrying frame.

16. In a printing device, a base, a slide rod rigidly mounted on said base, a carrying frame slidably mounted on said rod, a type form mounted pivotally parallel to said rod 65 in said carrying frame, type clamped in said form, a clamp screw extending longitudinally through the pivot with means for operating outside of the carrying frame, an inking pad and platen mounted on said base, 70 and means for sliding said carrying frame and form from the inking pad to the platen and back along said rod.

GEORGE W. HOLLINGSWORTH.
